UNITED STATES PATENT OFFICE.

GEORGE CLINTON MORTON ALLWORTH, OF WEST BAY CITY, MICHIGAN.

TOY.

No. 798,862.

Specification of Letters Patent.

Patented Sept. 5, 1905.

Application filed January 10, 1905. Serial No. 240,468.

To all whom it may concern:

Be it known that I, GEORGE CLINTON MORTON ALLWORTH, a citizen of the United States, residing at West Bay City, in the county of Bay and State of Michigan, have invented certain new and useful Improvements in Toys; and I do declare the following to be a full, clear, and exact description of the invention, such as will enable others skilled in the art to

10 which it appertains to make and use the same.

This invention relates to a sounding toy.

The object of the invention is to provide a toy in the shape of a box or package which when opened will produce a noise tending to surprise or frighten the holder of the box, the box preferably having the form and decoration of a candy, cigar, glove, or other familiar style of box in order to further deceive the person opening the same.

20 A further object is to provide a toy of this character which will be simple and inexpensive in construction and capable of creating considerable amusement.

With these and other objects in view the invention consists of certain novel features of construction, combination, and arrangement of parts, as will be hereinafter described and claimed.

25 In the accompanying drawings, Figure 1 is a plan view of the toy, showing the cover of the box removed. Fig. 2 is a similar view of the inside of the box-cover. Fig. 3 is a longitudinal vertical sectional view through the toy, and Fig. 4 is a transverse vertical sectional view of the same.

30 In the embodiment of the invention I provide a box or other suitable package or receptacle 1, which is preferably in the form of or simulating any well-known or familiar style 40 of box or receptacle—such, for instance, as a candy, cigar, or glove box. In the box is arranged an elastic connection, which is formed of any suitable material, but preferably consists and is here shown as a rubber band 2, 45 stretched across the box and having its ends secured to the sides of the same by means of wire staples 3 or any suitable connection.

45 Secured to the rubber band 2 is a tappet device 4, which may be of any suitable construction, but which preferably consists of a wire bent or looped upon itself to form spring clamping-arms by which it is secured to the rubber band. The ends or loops of the wire are adapted to be brought into rapid engagement with the bottom of the box, which is accomplished by winding or twisting the rub-

ber band in any suitable manner, but preferably by rotating the tappet-wire, after which upon releasing the same the rubber will rapidly untwist, thereby rapidly revolving the 60 tappet-wire in a reverse direction, the arrangement of the same being such that its ends will just strike the bottom of the box as they revolve, thus producing a series of rapid taps or knocks.

65 In order to hold the tappet device and rubber band against rotation when the box is closed, a transversely - disposed inwardly-curved bar 5 is arranged in the cover of the box in position to engage the tappet device 70 and prevent the same from revolving as long as the cover is in place, but which as soon as the cover is removed will be released, thus allowing the same to revolve and strike the bottom of the box.

75 The box may be made in any size and formed of any suitable material or combination of materials and is preferably provided with a tin or sheet-metal bottom in order to make a louder noise when struck by the tappet device.

80 A device constructed as herein described will be found to afford considerable amusement as a toy and may be also used in connection with various forms of advertising devices.

85 From the foregoing description, taken in connection with the accompanying drawings, the construction and operation of the invention will be readily understood without requiring a more extended explanation.

90 Various changes in the form, proportion, and the minor details of construction may be resorted to without departing from the principle or sacrificing any of the advantages of 95 this invention.

Having thus described my invention, what I claim as new, and desire to secure by Letters Patent, is—

1. In a toy, the combination with a hollow 100 receptacle, of an elastic connection stretched across the same, a tappet device secured to said flexible connection whereby when the latter is released after being wound or twisted the tappet-arm will be rapidly revolved and 105 caused to strike against the bottom of the receptacle thus producing a rapid tapping sound, a cover for said receptacle, and means whereby said connection and sounding device are held against rotation when said cover is in 110 place, substantially as described.

2. In a toy, the combination with a hollow

receptacle, of an elastic connection stretched across the same, a tappet device secured to said flexible connection whereby when the latter is released after being wound or twisted 5 the tappet-arm will be rapidly revolved and caused to strike against the bottom and the receptacle thus producing a rapid tapping sound, a cover for said receptacle, a curved cross-bar or strip arranged in said cover to hold said

tappet device against rotation when said cover is in place, substantially as described.

In testimony whereof I have hereunto set my hand in presence of two subscribing witnesses.

GEORGE CLINTON MORTON ALLWORTH.
